OWEN BROOKE EVANS, OF LANSDOWNE, PENNSYLVANIA, ASSIGNOR TO THE UNITED GAS IMPROVEMENT COMPANY, OF PHILADELPHIA, PENNSYLVANIA, A CORPORATION OF PENNSYLVANIA.

PROCESS OF BURNING SOLID FUEL.

1,085,806.

Specification of Letters Patent.

Patented Feb. 3, 1914.

Application filed March 20, 1913. Serial No. 755,575.

To all whom it may concern:

Be it known that I, OWEN BROOKE EVANS, a citizen of the United States, and a resident of Lansdowne, in the county of Delaware 5 and State of Pennsylvania, have invented a certain new and useful Process of Burning Solid Fuel, of which the following is a specification.

- The present invention is applicable to gas 10 producers, the combustion therein being incomplete and the gas generated conducted therefrom and used separately, and it is also applicable where the combustion within the device is complete.
- 15 The principal object is to prevent or minimize the agglutination in the form of so-called clinker of the partly melted residuum of the combustion of a bed of coal or fuel which has a fusible ash.
- 20 To this and other ends hereinafter set forth the invention, generally stated, consists in maintaining in the fuel bed superposed zones of relatively high and low temperatures, such as will and will not melt and 25 agglutinate the residuum or ash into clinker by apportioning the direction and quantity of flow of blast through them; feeding through the hotter zone a sufficient quantity of unburned fuel along with the residuum 30 or ash of the burned fuel for preventing agglutination of the partly melted ash or residuum into clinker; and feeding the last mentioned unburned fuel and divided residuum to the cooler zone and there burning 35 such fuel at a temperature insufficient to agglutinate the divided residuum.

The process of the invention will be claimed at the end hereof and can be practised by means of a great variety of apparatuses and alone or in connection with other industrial processes. However, it will be described in connection with the accompanying drawings, in which—

Figure 1, is a vertical section of one type 45 of gas producer, or generator. Fig. 2, is a similar view of another type, and Fig. 3, is a similar view of a third type.

Referring to the drawings, the bed of fuel is shown as contained in a generator 1, having one or more fuel intakes 2, a grate 8, openings 19 for removing the ash and an off-take 3, for the products of combustion, fuel gas or the like. As shown in Figs. 1 and 2, the grate is substantially flat and the fuel

is fed into the top of the generator, while 55 in Fig. 3, the grate is conical and the fuel is fed into the bottom of the generator by any well known type of under feed 21. Offtake 3 connects by means of the valves 4 and 5 to the top and bottom respectively of the 60 bed of fuel. In Figs. 1 and 3 the offtake does not extend into the generator beyond the lining, while in Fig. 2, it is extended by means of pipes 6 and 7 whereby the blast (either steam or air) may be admitted to 65 the axis of the generator, and the products of combustion, fuel gas, or the like, collected from a similar point. As shown in Figs. 1, 2 and 3, air or steam, or both, may be admitted below the grate by means of the 70 valved air connection 12, and the valved steam connection 13; or above the fuel bed by means of valved air connection 11 and valved steam connection 14, while in Fig. 2, in addition to these connections, additional 75 means are provided for introducing these fluids in the fuel bed through the offtake extensions 6 and 7 by means of the valved air connections 17 and 18, and the valved steam connections 15 and 16.

Zones 9 and 10 are superposed zones of 80 respectively relatively high and low temperatures; the high temperature zone being located between the low temperature zone and that end of the fuel bed to which fuel is fed, 85 for example, in Figs. 1 and 2, the high temperature zone 9 is above the low temperature zone 10, while in Fig. 3, their positions are reversed. These zones may extend horizontally clear across the fuel bed and may be of substantially uniform temperature throughout their extent. These zones are not sharply defined, although in fact they exist, and are maintained by proportioning and regulating the direction and quantity of 90 flow of blast through the fuel bed. The blast referred to is primarily intended to be an air blast such as is used in forced combustion or gas making, but it is not intended to exclude the use of steam, or air under 100 natural draft.

For the sake of further description and without intending to limit the claims, it may be said that when using the generator shown in Fig. 1 as a water gas generator the operation is as follows:—Assuming the generator to have been brought up to normal operation, valve 4 is opened and valve 5 closed.

Roughly, 20% of the total air supplied is then admitted below the grate by connection 12, the products leaving through off-take 3. 12 is then shut off, valve 4 is closed, 5 valve 5 opened, and the remaining 80% of air is admitted through connection 11, passing down through the fire to the offtake 3. 11, is then shut off, and roughly 40% of the total steam supplied is admitted through 14, 10 following the direction of the preceding blast. 14 and 5 are then closed, and 4 and 13 are opened, allowing the remaining 60% of the steam to travel up through the fire. 13 is then closed and blast again admitted 15 through 12, as above described.

The type of apparatus shown in Fig. 2 is to be preferred over that in Fig. 1, since by admitting all, or most of, the steam, or air, or other fluid to the fire by means of the 20 pipes 6 and 7, and subsequently withdrawing the products of combustion or fuel gas from the same pipes, there is a tendency for the fluids to pass through the axis of the bed of fuel, eliminating the objection hitherto experienced with apparatus of the type 25 shown in Fig. 1 in which the greater proportion of flow is next to the walls, and hence making the entire bed of fuel more active. In case the axis of the fire is doing 30 too much of the work, that part next the walls may be made more active by admitting some of the steam and air by means of the connections 11, 12, 13 and 14. Under such conditions the maximum temperature 35 in zone 9 may be, for example when using coke 2800° F. and the maximum temperature of zone 10, 2000° F., both more or less. The proportions and temperatures mentioned above are given merely as an example, 40 since these will vary considerably, depending upon the character of the fuel used as well as upon whether the fresh fuel is fed into the top or the bottom of the fuel bed. The temperature in the part of the 45 fuel bed, for convenience referred to as the zone 9, is sufficiently high to cause melting and agglutination of the residuum of combustion of the fuel which has a fusible ash into masses usually called clinkers, and the 50 temperature in the part of the fuel bed, for convenience referred to as the zone 10, is lower and is not sufficiently high to cause such agglutination, but in the zone 9 there is present sufficient carbon for preventing 55 agglutination into clinker of the fused or partially fused residuum, and the presence of this fuel in the zone 9 is insured by proper feeding. The fuel last referred to travels to and is consumed in the zone 10, 60 where the temperature is so low that agglutination into clinker of the divided residuum does not take place. Even if the temperature in the zone 9 is sufficient to fuse or melt the ash, there is carbon left in the material, 65 which carbon passes into the cooler zone and

is there burned because such carbon moves through the zone 9, to take the place of the carbon burned in the zone 10, or by reason of the removal of ash from the zone 10.

In the type of apparatus shown in Figs. 1 and 2 the feed is downward and is assisted by gravity, while in Fig. 3, the feed is upward and produced by mechanical means. It might be said that even if the conditions are favorable in the zone 9, for burning carbon, still the feed through that zone is so fast that all of the carbon in that zone is not burned. With the proper proportion of air flow the residuum is substantially free from clinker. If the proportion of air flowing through the fire in the general direction of the travel of the fuel, is increased beyond the proper figure, the combustion of fuel will be so localized as to produce a high temperature zone near that portion of the fire to which the fresh fuel is supplied, while at the same time the consumption of fuel in zone 10 will be so slow that the passage of the fuel through zone 9 is not sufficiently rapid to insure the presence of enough carbon in zone 9 to prevent the agglutination of the fused residuum into clinker. If the proportion of air flowing through the fire in the general direction of the travel of the fuel is reduced below the proper amount, the corresponding increase in the flow in the opposite direction will produce a temperature in zone 100 where the per cent. of carbon is low, above that of the fusing point of the ash and agglutinate the fused residuum into 100 clinkers.

While it is not new to blast up or down through the fire, it is believed that the proper proportioning of the blast to produce the result herein indicated has never before been suggested or attained.

For the sake of further description but without intending to limit the claims, it may be said that at one end of the fuel bed there is fuel, and at the other there is a divided 110 residuum of combustion, free, or at any rate substantially free from clinker, and that at the zone 9 there is present sufficient carbon for preventing agglutination of the fused or partly fused residuum, so that what is 115 known as clinker is practically absent. As an illustration and not to limit the claims, it may be said that in the zone 9, and in the case of coke, there is present about one-third carbon and two-thirds residuum. Incidentally, it may be remarked that for economic and other well known reasons it is necessary in the combustion of fuel which has a fusible ash to raise the temperature to a point at which such ash would, if unrestrained 120 and uncontrolled, agglutinate into masses called clinkers. By the present invention, however, the existence of these high temperatures, which are high enough to fuse the residuum, is limited to that portion of the 130

fuel bed which has sufficient carbon to prevent the fused residuum from agglutinating and in that way clinkers are avoided, while at the same time combustion of the fuel is satisfactorily carried on. It is hardly necessary to state that to remove clinkers is a laborious operation, and the presence of clinkers interferes with combustion, so that the importance of avoiding the formation of clinkers is obvious for these reasons, as well as for many other reasons, well known to those skilled in the art.

I claim:

1. The process of preventing the formation of clinkers in the combustion of a bed of fuel having a fusible ash, which consists in maintaining in the bed superposed zones of which one is at a temperature that would and the other is at a temperature that would not fuse ash by apportioning the distribution and changing the direction of application of the gas making fluids in respect to the zones, and preventing the agglutination of the fused ash into clinker by feeding unconsumed carbon through the hotter zone and burning such carbon in the cooler zone.

2. The process of preventing the forma-

tion of clinkers in the combustion of a bed of fuel having a fusible ash which consists in maintaining in the bed superposed zones 30 of which one is at a temperature that would and the other is at a temperature that would not fuse ash by apportioning the distribution and changing the direction and place of application of the gas making fluids in 35 respect to the zones, and preventing the agglutination of the fused ash into clinker by feeding unconsumed carbon through the hotter zone and burning such carbon in the cooler zone.

3. The process of preventing the formation of clinker in the combustion of fuel which consists in changing the direction of application of the gas making fluids to the bed to produce therein regions where ash 40 would and would not fuse, and feeding carbon along with the fused ash to prevent its clinkering and thereafter burning out the carbon when the ash is not fused.

OWEN BROOKE EVANS.
